CLAIM

The ornamental design for an insect trap, as shown and described.

DESCRIPTION

FIG. 1 is a perspective view from the front, top and left side, of an insect trap showing our new design;

FIG. 2 is a top plan view thereof;

FIG. 3 is a left-side elevational view, the right side being a mirror image thereof;

FIG. 4 is a front elevational view, the rear being a mirror image thereof; and

FIG. 5 is a bottom plan view thereof.
